US0D1055447S

(12) **United States Design Patent** (10) **Patent No.:** **US D1,055,447 S**
(45) **Date of Patent:** **** Dec. 24, 2024**

(54) **HANDLE COVER**

(71) Applicant: **Dajcor Aluminum Ltd.**, Chatham (CA)

(72) Inventor: **William J. Loucks**, Chatham (CA)

(73) Assignee: **Dajcor Aluminum Ltd.**, Chatham (CA)

(**) Term: **15 Years**

(21) Appl. No.: **29/864,105**

(22) Filed: **May 9, 2022**

Related U.S. Application Data

(63) Continuation of application No. PCT/CA2021/051472, filed on Oct. 19, 2021, and a continuation-in-part of application No. 16/873,941, filed on Aug. 20, 2020, now abandoned.

CLAIM

The ornamental design for a handle cover substantially as shown and described.

DESCRIPTION

FIG. 1 is a top view of the design, the bottom view being identical thereto.

FIG. 2 is a front elevation view of the design.

FIG. 3 is a rear elevation view of the design.

FIG. 4 is a right-side end view of the design, the left-side end view being a mirror image thereof.

FIG. 5 is a top right perspective view of the design.

FIG. 6 is an enlarged portion of the top right perspective view shown in FIG. 5; and,

FIG. 7 is another perspective view of the design.

The broken lines of FIG. 7 are to show environment and form no part of the claimed design.

1 Claim, 4 Drawing Sheets
